UNITED STATES PATENT OFFICE

RAYMOND E. PATTEN, OF OAK PARK, ILLINOIS, ASSIGNOR TO EDISON GENERAL ELECTRIC APPLIANCE COMPANY, INC., OF CHICAGO, ILLINOIS, A CORPORATION OF NEW YORK

DESIGN FOR AN ELECTRIC TOASTER

Application filed November 27, 1931. Serial No. 41,879. Term of patent 14 years.

To all whom it may concern:

Be it known that I, RAYMOND E. PATTEN, a citizen of the United States, residing at Oak Park, in the county of Cook, State of Illinois, have invented a new, original, and ornamental Design for an Electric Toaster, of which the following is a specification, reference being had to the accompanying drawing, forming a part thereof.

The accompanying drawing shows a per-

spective view of an electric toaster embodying my new design. The opposite side of the toaster has substantially the same appearance as the side shown in the drawing.

I claim:

The ornamental design for an electric toaster substantially as shown and described.

In witness whereof, I have hereunto set my hand.

RAYMOND E. PATTEN.
